James S. Jackson. Design for Banking

4379

PATENTED OCT 4 1870

James S. Jackson.

Chicago

for the Bank

Milwaukee

United States Patent Office.

JAMES L. JACKSON, OF NEW YORK, N. Y.

Design No. 4,379, dated October 4, 1870.

DESIGN FOR IRON-RAILING FOR HORSE-STALLS.

The Schedule referred to in these Letters Patent and making part of the same.

To all whom it may concern:

Be it known that I, JAMES L. JACKSON, of the city and State of New York, have invented or produced a new and original Design for an Iron Railing, and the following is declared to be a correct description thereof.

The vertical bars *r* are made with ornaments, *s*, at their lower ends, that connect the bars *r* to each other, and to the bottom rail *t*. These ornaments have openings through them, alternating in opposite directions, as shown, and leaflet branches are also employed, as represented.

At their upper ends, the bars *r* are connected by semicircular ornaments, *t'*, and leaflet scrolls, *u*, as represented.

The diamond-shaped connections *v*, between the bars *r*, do not form a necessary part of this design.

The general outline of this railing is straight at the bottom and at one end. The upper and lower parts of the railing are united by compound curved or ogee-top rails, as represented, so as to form a railing or ramp adapted to horse-stalls.

I claim as my invention—

The design of the configuration and ornamentation of the iron railing, substantially as described and represented.

Signed this 8th day of August, A. D. 1870.

Witnesses: JAMES L. JACKSON.

HAROLD SERRELL,
GEO. T. PINCKNEY.
